UNITED STATES PATENT OFFICE.

HORACE SEE, OF NEW YORK, N. Y.

ASH-EJECTOR.

SPECIFICATION forming part of Letters Patent No. 631,825, dated August 29, 1899.

Application filed May 4, 1899. Serial No. 715,532. (No model.)

To all whom it may concern:

Be it known that I, HORACE SEE, of the city, county, and State of New York, have invented a new and useful Improvement in Ash-Ejectors, of which the following is a specification.

My invention relates to that class of ash-ejectors employed on vessels in which the ashes are forced overboard through a discharge-pipe by means of a water-jet.

My invention consists in the construction of the apparatus whereby the valves controlling the discharge and also the actuating-jet may be operated simultaneously, also whereby the feed-door cannot be secured in open position until said valves are opened, also whereby the said valves cannot be closed while said feed-door remains in open position, also whereby the ashes are prevented from choking the delivery opening and the larger masses therein broken up, and also whereby the outgoing stream of ashes and water is directed toward the stern of the vessel, together with the various combinations of parts, all as hereinafter more particularly pointed out in the claims.

In the accompanying drawings, Figure 1 is a side elevation of my improved ash-ejector, showing the upper discharging-pipe in vertical section. Fig. 2 is a front view showing a portion of the hopper-door broken away. Fig. 3 is a top view with the upper portion of the hopper broken away to show the arrangement of the projections in the opening leading from the hopper to the discharge-pipe.

Similar numbers of reference indicate like parts.

1 represents the side of the vessel in section, in which my device is installed.

40 2 is a fore-and-aft bulkhead, in an opening in which the hopper is placed, so that said apparatus lies mainly between said bulkhead and the side of the vessel.

45 3 is a hopper provided with a flange 4, which rests against the inboard side of the bulkhead.

50 5 is a discharge-pipe which leads outboard from the hopper. The outboard end of the discharge-pipe enters an opening in the side of the vessel and is provided with a flange 6, bearing against the inside of the skin of said vessel. The inboard opening of the discharge-

pipe 5 is provided with a flange 7, which is bolted to a corresponding flange 8 on the hopper end. The opening 9 of the hopper, which 55 communicates with the discharge-pipe 5, is of less area than the said discharge-pipe at 10, so that any solid material which will pass through the opening 9 will also pass through the pipe in the direction of the arrow. In 60 the hopper-opening 9 are placed a number of solid projections 11, the function of which is to break up clinkers or other solid material in the ashes before the latter pass to the discharge-pipe.

65 12, Fig. 2, is a pipe leading from any source of water-supply under pressure and communicating with a suitable form of cock at 13. At 14 the water-conduit is reduced in area, so that when the water enters the discharge-pipe 70 5 it is delivered in the form of a jet directly through said discharge-pipe and so outboard. This jet is turned on and off and regulated by means of the valve or cock at 13. The rod which is connected to said cock and 75 through which said cock is turned to actuate it is shown at 15 and is journaled in a bracket 16. Secured to said rod at 17 is the operating-handle and also a projection 18 at an angle to said handle. The mouth of the hopper 80 is closed by a swinging door 19, hinged upon the rod 20 at the upper side of the hopper-mouth.

Pivoted upon the hopper-flange 4 are swinging bolts, one of which is shown at 21, Fig. 85 2, which bolts when the door is closed pass through openings in said door and receive nuts 22, provided with handles, by means of which nuts the door is fastened in closed position. The door may be provided on its inner side with packing, (represented at 23, Fig. 1,) in order that when shut it may make a close joint with the hopper-mouth. In the door is a small opening 24, wherein air is entrained when the device is in operation, which air 90 then produces a whistling sound, indicating that the apparatus is at work, and also prevents the formation of a partial vacuum in the hopper.

95 Pivoted in the discharge-pipe 5 upon a vertical shaft 25 is a valve 26, which may be swung into position longitudinally the pipe to open the delivery and transversely the pipe to close it. On the upper end of the

shaft 25 is secured an arm 27, to which is pivoted a link 28. The opposite end of said link is pivoted to an arm 29, which is fast upon the rod 15.

5 In order to operate the device, the rod 15 is turned, by means of the handle 17, so as to open the cock at 13 and allow the water-jet to pass outboard through the discharge-pipe 5. The handle 17 will then project outward, 10 as shown in Fig. 1, and by reason of the linkage 27 28 29 communicating with the valve 26 will place that valve in its open position, as shown. The air now being drawn in through the small opening 24 in the door will make 15 its whistling sound, indicating that the jet is in operation. The door is then swung upward, as shown by the dotted lines in Figs. 1 and 2, and is secured in that position by means of the pivoted bolt and nut 30. When 20 the door is in this upward position, it will be observed that the projection 18 on the rod 15 comes behind it, so that the rod 15 can now not be turned by its handle 17 to shut off the water-jet until the door is closed. The ashes 25 to be ejected are now thrown into the hopper 3 through the door-opening. They pass through the hopper-opening 9, the larger masses being broken by the projection 11, as already explained, and thence into the discharge-pipe 5, where the water-jet from 14 meets them and forces them out through the outboard delivery-opening.

It will be seen that the arrangement for preventing the rod 15 being turned to close 30 the water-jet while the hopper-door is open obviates any danger of ashes being put into the hopper when there is no jet working to force them overboard, and thus any possible clogging of the apparatus is avoided.

40 The discharge-pipe 5 is, as best shown in Fig. 3, arranged at an angle to the fore-and-aft line of the vessel, so that the material is discharged in a direction toward the stern. The object of this is to reduce the resistance 45 which might be offered when the vessel is in motion and going ahead, especially when the discharge-pipe is located below the water-line, to the outward movement of the ejected material. In Fig. 1 I have shown the water-line at A as above the discharge-opening and at B as below it. It will be understood from this that the apparatus may be disposed so as to deliver either above or below the water-level.

55 It will be obvious that when the rod 15 is turned so that the projection 18 thereon extends outwardly from the bulkhead 2 the door 19 cannot be swung upward to be engaged by the pin and nut 30, Fig. 1; or, in 60 other words, the projection 18 must be put into the position shown in Figs. 1 and 2 before the door can be secured in its open position; but when the projection extends outward, as stated, the water-valve at 13 and the valve 65 26 in the discharge-pipe are closed. Hence the rod 15 must be turned to open said valves and bring the projection 18 into the position

shown in Figs. 1 and 2 before the door can be secured, as stated.

I claim—

1. The combination in an ash-ejector of a discharge-pipe, a valve therein, means for producing a jet of water communicating with said discharge-pipe, a valve controlling said jet, and means for simultaneously opening 75 and closing said valves, substantially as described.

2. The combination in an ash-ejector, of a discharge-pipe, a valve therein, means for producing a jet of water communicating with 80 said discharge-pipe, a valve controlling said jet, and mechanism between said valves, whereby one of said valves cannot be operated without also operating the other, substantially as described.

3. The combination in an ash-ejector of the discharge-pipe 5, valve 26 therein, jet-pipe 14 communicating with pipe 5, valve 13 controlling the jet in pipe 14, valve-rod 24 and linkage 27, 28, 29 between said valves, substantially as described.

4. The combination in an ash-ejector of a receptacle for the ashes, means for closing the feed-opening thereof, a discharge-pipe communicating with said receptacle, means for 95 producing a water-jet communicating with said discharge-pipe and means for preventing the shutting off of said jet when the feed-aperture of said receptacle is open, substantially as described.

5. The combination in an ash-ejector of a receptacle for the ashes, a door at the feed-opening thereof, a discharge-pipe communicating with said receptacle, means for producing a water-jet communicating with said discharge-pipe, a valve or cock controlling said jet, and means controlled by said door for preventing the closing of said valve or cock while said door is open, substantially as described.

6. The combination in an ash-ejector of a receptacle for the ashes, an upwardly-swinging door at the feed-opening thereof, a discharge-pipe communicating with said receptacle, means for producing a water-jet communicating with said discharge-pipe, a valve controlling said jet, a rod for actuating said valve and a projection extending from said rod; the aforesaid parts being constructed and arranged so that when said valve is opened by turning said rod, and said door is swung upward, said projection shall be retained by said door to prevent said rod being turned to close said valve, substantially as described.

7. The combination in an ash-ejector of a receptacle for the ashes, means for closing the feed-opening thereto, a discharge-pipe communicating with said receptacle, means for producing a water-jet communicating with said discharge-pipe, a valve in said discharge-pipe and means for preventing the closing of said valve while the feed-aperture of said receptacle is open, substantially as described.

8. The combination in an ash-ejector of a

receptacle for the ashes, a door at the feed-opening thereof, a discharge-pipe communicating with said receptacle, means for producing a water-jet communicating with said discharge-pipe, a valve in said discharge-pipe and means controlled by said door for preventing the closing of said valve while said door is open, substantially as described.

5 9. The combination in an ash-ejector of a receptacle for the ashes, a door at the feed-opening thereof, a device for holding said door open, a discharge-pipe communicating with said receptacle, means for producing a water-jet communicating with said discharge-pipe, a valve controlling said jet, and means for preventing said door from being held in open position until said water-jet valve shall have been first opened, substantially as described.

10 10. The combination in an ash-ejector of a receptacle for the ashes, a door at the feed-opening thereof, a device for holding said door open, a discharge-pipe communicating with said receptacle, a valve in said discharge-pipe, means for producing a water-jet communicating with said discharge-pipe, and means for preventing said door being held in open position until said discharge-valve shall have been first opened, substantially as described.

11 11. The combination in an ash-ejector of a receptacle for the ashes, a door at the feed-opening thereof, a device for holding said door open, a discharge-pipe communicating with said receptacle, a valve in said discharge-pipe, means for producing a water-jet communicating with said discharge-pipe, a valve controlling said jet, and means for preventing said door from being held in open position until both of said valves shall have been first opened, substantially as described.

12 12. The combination in an ash-ejector of a receptacle for the ashes, a swinging door at the feed-opening thereof, a discharge-pipe communicating with said receptacle, means for producing a water-jet communicating with

1 said discharge-pipe, a valve in said discharge-pipe, a rod for actuating said valve and a projection extending from said rod; the said parts being constructed and arranged so that when said door is swung to definite open position said projection shall be retained by said door to prevent said rod from being operated to close said valve, substantially as described.

50 13. The combination in an ash-ejector of a receptacle for the ashes, means for closing the feed-opening thereto, a discharge-pipe communicating with said receptacle, means for producing a water-jet communicating with said discharge-pipe, a valve in said discharge-pipe, a valve controlling said water-jet and means for preventing the closing of said valves when the feed-aperture of said receptacle is open, substantially as described.

55 14. In an ash-ejector, arranged in a boat or vessel, a discharge-pipe for the ashes, extending from inboard outwardly to the side of the vessel and inclined aft to project the ashes overboard in a direction toward the stern of said vessel, and a water-jet communicating with said pipe and operating to force the ashes through the same, substantially as described.

60 15. In an ash-ejector wherein the ashes are ejected by means of a water-jet, an ash-receptacle having a door and an opening in said door through which air is drawn by the action of said jet, substantially as described.

65 16. In an ash-ejector, the combination of the hopper 3, discharge-pipe 5, jet-pipe 14 communicating with a source of water under pressure, valve 26 in said discharge-pipe, valve 13 regulating the flow of water to said jet, rod 15, connections 27, 28, 29 between said rod 15 and said valve 26, projection 18 on said rod, and swinging door 19, substantially as described.
